UNITED STATES PATENT OFFICE.

HUGH COLL, OF MILLVALE, PENNSYLVANIA.

IMPROVEMENT IN WATER-EJECTORS.

Specification forming part of Letters Patent No. 143,884, dated October 21, 1873; application filed August 22, 1873.

To all whom it may concern:

Be it known that I, HUGH COLL, of Millvale borough, in the county of Allegheny and State of Pennsylvania, have invented a new and useful Improvement in Water-Ejectors; and I do hereby declare the following to be a full, clear, and exact description thereof, reference being had to the accompanying drawing forming a part of this specification, in which—

Figure 1 is a longitudinal section, and Fig. 2 is a cross-section, of my improved siphon-pump.

My invention consists of the hereinafter described and claimed improvements in water-ejectors.

To enable others skilled in the art to make and use my invention, I will describe its construction more fully.

The outline of the shell A is of regular spherical shape in cross-section. The receiving-chamber is formed below and outside of the discharge-chamber, which is in itself of perfectly regular cylindrical shape in cross-section, as shown in Fig. 2. The forward end of the discharge-chamber is drawn down to form a nozzle, which corresponds in shape to that shown in the patent granted to me December 20, 1870. The receiving-chamber a is separated from the discharge-chamber b by means of a diaphragm, c, which extends across the lower portion of the shell A. This diaphragm is provided with an opening, e, at the rear end of the receiving-chamber, whereby the latter communicates with the discharge-chamber. The diaphragm, together with the upper portion of the shell d, forms a perfect circle. (See Fig. 2.) The injection or steam pipe f enters at the rear end of the shell A, as usual, and projects a short distance beyond the opening between the receiving and discharge-chambers. At its forward end the discharge-chamber is drawn down to form a nozzle, h, the outer end of which is threaded internally to form a socket, h', for the discharge-tube.

The operation of this pump is the same as that of its class. The jet of steam driving out the air, &c., from the discharge-chamber b, creates a partial vacuum, and thereby elevates the water through the induction-tube, which is attached to the socket h, whence it passes into the receiving-chamber a, thence through the opening e into the discharge-chamber, and out through the nozzle.

By my improvement I am enabled to reduce

the amount of material that is necessary in the construction of this class of siphon-pumps, and by forming the whole shell in one piece by casting I very much simplify the manufacture, and at the same time strengthen the shell. By forming the receiving-chamber outside of the discharge-chamber, so as not to alter the symmetry of the discharge-chamber, I am enabled to preserve one of the features of the double-headed siphon-pump—that is, to reduce to a minimum the friction in the discharge-chamber. It is evident that if there were any irregularities in the curve of the outlines of the discharge-chamber a corresponding amount of friction would be produced. This, of course, is objectionable.

I have found that it is not necessary for the purpose for which the double-headed pump was made that the receiving-chamber formed between the inner and outer heads should extend entirely around; hence I make this receiving-chamber on the lower side only, while the diaphragm acts as a break-water to destroy the force of the inflowing current and prevent it from coming directly in contact with the jet of steam. Thus I secure all the advantages of the double-headed pump, and at the same time save a large portion of the material which has heretofore been necessary in making the inner head, and simplify the construction of the pump.

What I claim as my invention, and desire to secure by Letters Patent, is—

1. A siphon-pump in which the receiving-chamber is formed by means of a diaphragm extending across the lower portion of the shell, such diaphragm forming part of the shell and having an opening, e, at the rear of the steam-nozzle, whereby the water is admitted into the discharge-chamber, substantially as described.

2. The shell d, cast in one piece, of a regular spherical form, in cross-section, having a diaphragm, c, which, with the upper portion of the shell, forms a circular discharge-chamber, b, of smaller diameter, the receiving-chamber a being the lower or eccentric portion of the shell, substantially as described.

In testimony whereof I, the said HUGH COLL, have hereunto set my hand.

HUGH COLL.
